UNITED STATES PATENT OFFICE

WILLIAM A. READY, OF BROOKLINE, MASSACHUSETTS

PIGTAIL FOR VARIABLE ELECTRIC CIRCUIT TUNING DEVICES

Application filed April 24, 1930. Serial No. 446,987.

My invention aims to provide improvements in variable electric circuit tuning devices and is directed particularly to that part of the device commonly called the "pigtail".

5 In the drawings which illustrate a preferred embodiment of my invention:

Figure 1 is a longitudinal cross-section through a portion of a variable condenser for radio apparatus; and

10 Fig. 2 is an end elevation of the device shown in Figure 1 as it appears when viewed from the left.

Referring now to the embodiment of my invention illustrated by the drawings I have 15 shown a variable air condenser equipped with a flexible constant inductance member which I shall hereafter refer to as a "pigtail" 1. While I have illustrated the use of my invention in connection with a condenser substantially the same in construction as shown and more fully described in my United States Letters Patent No. 1,756,570, it should be understood that the "pigtail" may be used with the same improved results in connection with 20 variometers, variocouplers, etc.

The condenser shown in the drawings is of the "short wave" type and has a rotor which comprises the plates 2 and the shaft 3, and a stator, comprising fixed plates 4 (portions only of which are shown in Figs. 1 and 2) and a frame 5 (a portion only of which is shown). The rotor shaft 3 is shown with one end mounted for rotation in an adjustable bearing 6.

35 While the "pigtail" 1 may be mounted in a number of different ways, I have shown a simple and compact manner of doing so in connection with a condenser. The shaft 3 and bearing 6 are bored axially and one end

40 of the "pigtail" 1 is soldered or otherwise secured to the rotor at the inner end of the bore 7, while the other end is soldered to a terminal member 8 secured to the frame 5. Thus, I have secured the "pigtail", which 45 may be braided or stranded wire, in such a manner that it is in a straight line with the axis of the rotor.

I am aware of the fact that various types 50 of "pigtailed" have been used heretofore to secure a positive connection between a rotor

and a terminal, but so far as I am aware no one has ever used a constant inductance "pigtail". Heretofore, the type of "pigtail" used and its assembly were such that the inductance of the "pigtail" varied as the rotor was turned. This change in inductance of the "pigtail" affects the circuit and prevents securing accuracy in adjustment which is essential as, for instance, in so-called "short wave" radio apparatus. It is to correct these inaccuracies and permit precision adjustment of a variable circuit tuning device that I have invented my constant inductance "pigtail".

I have found that by arranging the flexible wire (pigtail) in a straight line and using braided or stranded wire the wire merely twists about an axis without changing the inductance effect in the "pigtail".

As a result of my invention, I secure a direct and positive electrical connection between a wire 9 in a circuit and the rotor. Furthermore, the rotation of the rotor to adjust the circuit does not change the inductance of the "pigtail", because of the fact that the effective relation of the "pigtail" to the surrounding energized parts does not change. This results in more accurate and easier adjustment of a given circuit, because by having the inductance of the "pigtail" 1 constant it cannot affect or interfere with the changes brought about by the rotation of the plates 2 relative to the plates 4.

While the sleeve 10 (Fig. 1) of insulating material is not absolutely essential, it is desirable, because it will prevent contact of the "pigtail" 1 with either the shaft 3 or the frame 5. If the "pigtail" 1 should contact with the shaft 3 or frame 5 intermediate its fixed ends, a sort of "short-circuiting" effect would take place and thereby change the inductance of the "pigtail" 1.

While I have illustrated and described a preferred embodiment of my invention, I do not wish to be limited thereby, because the scope of my invention is best defined in the following claims.

Claims—

1. An electric circuit tuning device having a rotor, a frame supporting the rotor, a flexible electrical conductor of fixed induc-

tance connecting the rotor and a terminal supported by the frame, said flexible conductor being located in line with the axis of the rotor, thereby to twist throughout its length to prevent capacity changes in the rotor, and an insulating material surrounding said flexible conductor to prevent contact with the rotor or frame intermediate its fixed ends.

10 2. In a variable electric circuit tuning device, a flexible "pigtail" conductor constructed and arranged to provide a constant inductance therein at all times, and an insulator surrounding said flexible conductor to prevent short-circuiting thereof with the said device.

15 3. An electric circuit tuning device having a rotor, a frame supporting the rotor, a terminal secured to said frame, means providing a bore in said frame and in said rotor, a constant inductance flexible conductor located in said bore and having one end fixed to said rotor and the other end being fixed to said terminal, and an insulating tubular sleeve located in said bore and surrounding said flexible conductor between its fixed ends.

20 In testimony whereof, I have signed my name to this specification.
